DESIGN FOR A TELEPHONE STAND OR SIMILAR ARTICLE

Oliver Reagan, Westport, Conn., assignor to American Telephone and Telegraph Company, a corporation of New York

Application August 16, 1933. Serial No. 49,038

Term of patent 14 years

To all whom it may concern:

Be it known that I, OLIVER REAGAN, a citizen of the United States, residing at Westport, in the county of Fairfield and State of Connecticut, have invented a new, original, and ornamental Design for a Telephone Stand or Similar Article, of which the following is a specification, reference being had to the accompanying drawing, forming a part thereof.

The figure is a perspective view of a telephone stand or similar article, showing my new design.

I claim:

The ornamental design for a telephone stand or similar article, as shown.

In witness whereof, I hereunto subscribe my name this 11th day of August, 1933.

OLIVER REAGAN.
